CLAIM

The ornamental design for a light fixture, as shown and described.

DESCRIPTION

This application is related to commonly assigned application Ser. No. 10/757,628 filed Jan. 14, 2004, now U.S. Pat. 7,101,065, and to commonly assigned, concurrently filed application Ser. No. 29/221,163, application Ser. No. 29/221,162 and application Ser. No. 29/221,195.

FIG. 1 is an isometric view of the light fixture of the present invention;

FIG. 2 is a front elevation view thereof;

FIG. 3 is an enlarged front elevation view thereof without environmental structure, the side and rear elevation views being identical thereto;

FIG. 4 is a bottom plan view thereof;

FIG. 5 is a top plan view thereof; and,

FIG. 6 is a front elevation view of a second embodiment, the side and rear elevation views being identical thereto;

FIG. 7 is a front elevation view of a third embodiment, the side and rear elevation views being identical thereto;

FIG. 8 is a front elevation view of a fourth embodiment, the side and rear elevation views being identical thereto; and,

FIG. 9 is a front elevation view of a fifth embodiment, illustrating a smaller fixture which is otherwise the same as the first embodiment.

The broken line showing is for illustrative purposes only and forms no part of the claimed invention.
